UNITED STATES PATENT OFFICE.

ISAAC NEWTON SMITH, OF GREENVILLE, OHIO.

BURIAL-COUCH.

1,255,941.

Specification of Letters Patent. Patented Feb. 12, 1918.

Application filed April 12, 1917. Serial No. 161,586.

To all whom it may concern:

Be it known that I, ISAAC NEWTON SMITH, a citizen of the United States, residing at Greenville, in the county of Darke, State of Ohio, have invented a new and useful Burial-Couch; and I do hereby declare the following to be a full, clear, and exact description of the invention, such as will enable others skilled in the art to which it applies to make and use the same.

The invention is a burial couch.

It seeks to provide, as one of its objects, a neat and inexpensive couch of this character to be used in conjunction with stone burial vaults, taking the place of the heretofore heavy and expensive caskets.

A further object is to provide a couch of this kind adapted to have a silk or leather covering and to make the whole of such a design and construction that it may be folded up compactly.

Other objects will appear in the detailed description which follows.

Should the drawings and specification vary to the extent of having the one set forth some detailed structure which is not fully defined by the other, the right to such structure is claimed as though it had been fully treated by both.

The drawings illustrate a particular design to which, however, the invention is not to be restricted. The right is reserved to make any changes or alterations suggested by the demands of practice, provided such changes or alterations are compatible with the spirit of the appended claim.

The same numerals of reference designate the same parts throughout the several figures of the drawings, wherein:

40 Figure 1 is a side elevation of the invention.

Fig. 2 is a longitudinal sectional view.

Fig. 3 is a bottom plan view, showing the supporting legs in their folded position.

45 Fig. 4 is a plan view of the invention in its folded up position.

Fig. 5 is a detail view of one of the joints between the hood braces, showing the manner in which these braces are connected to the frame.

50 In the drawings, the numeral 1 represents the bottom which comprises two frames joined together by the hinges 2, each frame being made up of the end pieces 4 and side pieces 3. Each frame is provided with a wire mesh 5 suitably affixed to its side and

end pieces and is further provided with a covering 6 secured to the side and end pieces and covering both them and the mesh 5. Near the ends remote from the hinges 2, 60 the legs 7 are pivotally connected with the frames, as at 8, the pivotal connection of each leg being on the inner edge of the side piece 3. The transverse piece 9 joins together the two legs 7 of each frame, effecting 65 a rigid connection between them. The legs of each frame with their transverse piece 9 are adapted to fold up between the side pieces 3 in the space below the wire mesh 5. When the legs 7 are lowered, they 70 are limited in the turning movement on the pivotal connections 8 by the blocks 10 which are suitably fixed in the corners formed by the ends 4 and the side pieces 3, the legs abutting these blocks after passing a perpendicular position with respect to the bottom 1. When the legs abut the blocks they 75 are precluded from further movement and thus serve to support the bottom 1 above the floor. 80

Collapsible hoods 11 and 12 are suitably affixed to the bottom 1 at the ends thereof, each of the two frames comprising the bottom carrying one of the hoods. Each hood comprises the U-shaped supporting braces 85 15, 16 and 17 to which a suitable covering, preferably silk or leather is attached by convenient rivets 18. The covering for hood 11 and designated as 14 terminates at the brace 16, but the covering for hood 12 90 (designated as 13) extends beyond its brace 16 being made long enough to project just over the end of hood 11 where buttons 19 or other suitable attachments effect this connection with hood 11. Beside their connection with the U-shaped braces coverings 14 and 13 are attached to the ends 4 and sides 3 by any suitable means 20, the covering 13, however, not being connected to the side pieces 3 beyond the point where it is 100 attached to its U-shaped brace 16.

The manner in which the U-shaped braces are attached to the frames comprising the bottom 1 is shown in detail in Fig. 5. The braces 16 and 17 have angled ends 23 105 and 24 respectively while the brace 15 is straight. The three braces are joined together by the pivotal connection 22 which connects the angled ends 23 and 24 of braces 16 and 17 with the end of brace 15. A pivotal connection 21 effected at the point where the angled end 24 connects with the brace

17 serves to attach all three braces to the side piece 3. The description of the connection between the U-shaped braces at their attachment to the bottom 1 has been referred to in the singular, but it is, of course, understood that there are two of these connections for each hood, one on each side of each of the two frames comprising bottom 1. When the hoods are collapsed, the braces 16 and 15 are turned back against the braces 17 on the pivotal connections 22 and all are then turned back on the frames comprising the bottom by means of the pivotal connections 21.

15 U-shaped handles 25 are provided for carrying the couch when it contains a corpse. These handles are affixed to the bottom 1, one handle being attached to each of the side pieces 3. The legs of the handles pass 20 through holes formed on the outer edge of the pieces 3. Suitable washers 26 which are countersunk in said pieces 3 are affixed to the legs of the handles and effect their attachment to the pieces 3 but permitting 25 them to be slid in and out, so that the handles may be slid out to provide a hand grip when the couch is being carried or slid in out of the way when the latter is collapsed.

30 From the drawings it is apparent how the couch may be collapsed. The hoods 11 and 12 are first collapsed by folding down upon the bottom 1. The two sets of legs 7 are then folded up against the wire mesh 5, when the two frames comprising the bottom 35 are then folded together on the hinges 2. In this collapsed condition the couch is easy to transport and takes up a small amount of space.

40 The couch is designed for use in conjunction with a stone burial vault, it being placed

in such a vault with the corpse which it holds after the legs 7 have been folded up beneath the bottom. The handles 25 are adapted for use in carrying the couch when it holds the corpse but may be slid in out 45 of the way when not in use and when the couch is collapsed. The hoods 11 and 12 with their attendant covering form an acceptable means for covering the corpse when it is placed in the vault. 50

What is claimed is:

In a collapsible burial couch, a pair of rectangular skeleton frames hingedly united at their adjacent edges, whereby the opposite ends of said frame may collapse downwardly and toward each other, a piece of wire fabric stretched over each frame, a canvas covering on the frame over the fabric, a pair of blocks, one secured in each of the outermost corners of each frame, a pair of 55 legs, one pivoted to each of the side rails of each frame adjacent said block, whereby the leg may abut the block to reinforce the leg when in supporting position, and whereby the leg may collapse within the frame when the frame is collapsed, an arched covering for the outer end of one frame, pivoted 60 arched braces therefor, an arched covering for the other frame extending over the first frame and overlapping and being detachably connected to the first arched covering, and pivoted arched braces for the second arched covering. 65

In testimony whereof I have signed my name to this specification in the presence of 70 two subscribing witnesses.

ISAAC NEWTON SMITH.
